SAFETY WATCH POCKET FOR GARMENTS

Charles Rosco Wood, Red Boiling Springs,
Tenn.Application October 24, 1933, Serial No. 695,009
In Canada April 22, 1933

7 Claims. (Cl. 2—254)

This invention relates to safety watch pockets for garments and embraces pocket structures arranged to provide a combination of pockets.

An object of the present invention is to provide a safety watch pocket of a nature simple to make up, which will securely retain a watch under all conditions.

A further object of the invention is to provide a pocket of this character which, in providing for safely carrying a watch, will provide in a compact structure a plurality of pockets which may be used for other articles.

A further object of the invention is to provide a pocket of reinforced character.

With these and other objects in view the invention consists essentially of a pocket formed from two pieces of material sewn to a backing and overlapped one upon the other and secured together in spaced apart seams to provide a plurality of adjacent pockets the fastening means of which will form means for preventing a watch from dropping from the pocket under all conditions while providing for the normal removal without difficulty, as more fully described in the following specification and illustrated in the accompanying drawing which forms part of the same.

In the drawing,

Figure 1 is a fragmentary view of the upper part of the bib of an overall, illustrating the improved pocket mounted thereon, part of the pocket being shown in section.

Figure 2 is a section taken on the line 2—2 of Figure 1.

Figure 3 is a section taken on the line 3—3 of Figure 1.

Figure 4 is a section taken on the line 4—4 of Figure 1.

Figure 5 is a section taken on the line 5—5 of Figure 1, and

Figure 6 is a section taken on the line 6—6 of Figure 1.

Referring particularly to the drawing, A indicates the portion of any suitable garment such as the bib of an overall upon which the improved pocket B is secured. According to the invention the pocket is made up of two main pieces or sections 10 and 11, the construction being such that the pieces are cut so that there are no proper rights or lefts to the pocket pieces, it being merely necessary that the proper end and side of the pieces be hemmed in order that the watch pocket may be formed on the left side of the bib of an overall or the like. Throughout the description reference to the right or left hand side of the bib

or sections means the right or left hand side as worn and not as viewed.

The section 10 is materially larger than the section 11 and approximately one-half of this section is positioned on the right hand side of the bib of the overall, being secured thereto by seams 12 around its outer edges and a seam 13 approximately in the middle of the section so that a book pocket 14 is provided on the right hand side of the bib which may be closed by a suitable flap 15 secured to the bib above the pocket. In this connection it will be noted that the seam 13 coincides with the centre seam of the overall bib. The remaining portion of section 10 projects to the left hand side of the bib from the centre seam 13 and section 11 is overlapped thereon to a considerable extent and for a distance at least exceeding a double row of stitches ordinarily employed in garment construction of this character.

Section 11 is preferably of greater length than section 10 and is secured to the overall bib by a continuation of the seam stitching 12 extending along its bottom as at 15', the left hand side as at 16 and the top as at 17. The upper corner of the section 11 is turned in to provide an inclined side on the piece which uncovers the upper edge of section 10 between which and the bib pocket openings are formed. Between section 10 and that area of section 11 adjacent to the inclined edge, an opening to this watch pocket is formed.

The turned in corner of section 11 is secured in its folded in position by means of stitching providing within the pocket an apron 18. The apron may be secured to the inner side of section 11 by means of the marginal inclined row of stitching 19 or the inclined row of stitching 20, as shown in Figure 1, or both rows of stitching may be employed.

The free end or left hand corner of section 10 underlying section 11 is secured to the bib by suitable bar tacking 21 at its upper corner while the left hand edge 22 is left throughout its length without being secured to the bib. On the contrary the lower portion of this free or left hand edge 22 is secured to the section 11 by means of the stitching 23 while the right hand edge of section 11 is secured to the underlying portion of section 10 by means of the stitching 24 so that between the sections 10 and 11 a further pocket is formed defined by the stitching 15' at the bottom and the stitching 23 and 24 on each side, the opening to the pocket being at the top and accessible through the main opening to the watch pocket. Suitable reinforcing bar tacking 25 is inserted at the top of this pocket extending only

between sections 10 and 11 while bar tacking is also inserted at the opposite side of the top of this pocket as at 26, this bar tacking extending through the sections 10 and 11 and also through the bib of the overall. In this way the watch pocket is defined, being margined by the stitching 13, 15', 16 and 17, the bar tacking 26, bar tacking 21 and bar tacking 28 and being formed by both the sections 10 and 11. The watch is introduced through the pocket opening 27 between the overlapping portions of sections 10 and 11 and after passing through this opening drops behind the left hand edge of section 10 to repose there-beneath and beneath section 11 confined by the margins referred to.

The upper portion of section 10 extending on the left hand side of the bib, except for bar tacking 21 and the bar tacking 28, is left free so that between the bar tacking 21 and 28 and the seamings 13 openings are provided between the bib and this section to form two pockets which may be used as pencil pockets or pencil and rule pockets. Therefore, on one side of the bib four pockets are formed in the arrangement of the sections 10 and 11 in a compact easily made pocket construction and the stitching forming these various pockets serves in each case as a medium for retaining the watch within the main watch pocket as referred to hereinafter.

30 The two pockets referred to, the openings to which are provided at the upper edge of section 10 between the bar tacking 21 and 28 and the seam 13, communicate with the interior of the main watch pocket but articles carried in the 35 two pockets referred to will not interfere with the retention of the watch within the watch pocket. While these additional pockets communicate with the interior of the watch pocket it will be noted that the bar tacking 26 which is 40 substantially in line with the back tacking 28, forms a further division between the two pockets referred to since the bar tacking 26 extends completely through section 11, section 10 and the 45 backing upon which the pocket structure is mounted.

It will be realized that the salient feature underlying the construction consists in providing a plurality of pockets through the arrangement of two pieces of material sewn to a backing at a 50 majority of their marginal edges and sewed together in spaced apart separate seams at those marginal edges overlying and underlying respectively the opposite piece, a number of pockets being provided between the pieces and the backing and an additional pocket formed between the pieces and the spaced apart seams referred to, which sew the pieces or sections together. In 55 each instance I have illustrated the seams of the pocket as the conventional double reinforcing 60 seams but these might be single if desired. This double seaming should, therefore, not be confused with the spaced apart seams described.

It is not necessary, of course, that the book 65 pocket should be formed to provide the structure referred to but it will be realized that in two simple pieces of material I have provided an arrangement which may form five pockets in a compact manner, including a watch pocket, book 70 pocket, pencil pocket and rule pocket or these pockets may be used for various articles. Furthermore, it will be realized, of course, that it is not necessary for the section 11 to extend to a 75 level above that of section 10 as shown, since the construction would function in exactly the same

manner if section 11 terminated along the level of the upper edge of section 10.

In use it will be seen that once the watch is inserted into the watch pocket through the opening 27, it will drop into the watch pocket to be held behind the left hand portion of section 10 which, up to the bar tacking 26, is secured to section 11. It cannot return through the main pocket opening in the case where the wearer should bend over because in this instance it will contact with the bar tacking 21 or 28 or with the stitching 17.

On the other hand, if the watch is located within the left hand side of the pocket and the wearer of the garment bends over with a swinging motion such as to move the watch in a direction towards the pocket opening it will merely slide behind the left hand side of section 10 or the apron 18 will tend to stop its progress and direct it back into other portions of the pocket so that the watch will be securely held within the pocket under abnormal conditions. The chain or retaining member, therefore, provides the only certain way of removing the watch from the pocket. In this way I have provided an effective main safety 25 watch pocket of simple character while providing for a combination of pockets.

Various modifications may be made in this invention without departing from the spirit thereof or the scope of the claims, and therefore the 30 exact forms shown are to be taken as illustrative only and not in a limiting sense, and it is desired that only such limitations shall be placed thereon as are disclosed in the prior art or are set forth in the accompanying claims.

I claim:—

1. Pocket structure, comprising two pieces of material sewn to a backing to provide with said backing a plurality of pockets, said pieces being offset with respect to each other overlapped and secured together to provide between the overlapped portions of said pieces an additional pocket.

2. The device as claimed in claim 1, in which the additional pocket between the pieces is superimposed over a pocket formed between one piece and the backing.

3. Pocket structure, comprising two pieces of material sewn to a backing to provide with the backing a plurality of pockets, one of said pieces being sewn to the backing around two of its marginal edges and secured to said backing in at least two places on a third marginal edge, the second piece of material being overlapped on said first piece and sewn to a backing around three of its marginal edges, said pieces being sewn together throughout a length of their fourth marginal edges in spaced apart seams forming the side seams of a pocket provided between the pieces, one of said latter seams securing the pieces together, forming with the backing and pieces a main safety pocket having an opening above said latter seam accessible between said pieces.

4. Pocket structure, comprising two pieces of material sewn to a backing to provide with the 65 backing a plurality of pockets, one piece being sewn to the backing throughout two of its marginal edges, left free from the backing along one marginal edge and tacked to the backing at spaced apart points along a fourth marginal edge, 70 the second piece being overlapped on the first piece and sewn to the backing throughout three of its marginal edges, the free marginal edge of the first piece being sewn throughout a portion of its length to the overlying second piece, the 75

free marginal edge of the second piece being sewn throughout a portion of its length to the first piece, the edge of the second piece between the termination of the latter mentioned sewing and 5 one of the edges sewn to the backing being left free to provide an opening to one of the pockets.

5. The device as claimed in claim 4, in which the free edge of the second piece forming the opening to one of said pockets is arranged at an 10 incline to other edges of the piece to leave uncovered an opening to another pocket formed between the tacking securing one edge of the first piece to the backing.

6. Pocket structure, comprising two pieces of 15 material sewn to a backing to provide with said backing a plurality of pockets, said pieces being

offset with respect to each other overlapped and secured together to provide between the overlapped portions of said pieces an additional pocket, one of said pieces being secured to the backing by a seam spaced from and parallel with a marginal seam to provide a further pocket. 5

7. Pocket structure comprising two pieces of material and a backing, said pieces being sewn to the backing at a majority of their marginal edges, and offset with respect to each other, overlapped, 10 and sewn together independently of the backing in spaced apart separate seams at those marginal edges overlying and underlying respectively, the opposite piece.

CHARLES ROSCO WOOD. 15
